Specification for Design.

Patented Mar. 9, 1920.

Application filed March 21, 1919. Serial No. 284,218. Term of patent 3½ years.

To all whom it may concern:

Be it known that I, FRANK M. NOONAN, a citizen of the United States, residing at Boston, in the county of Suffolk and State of Massachusetts, have invented a new, original, and ornamental Design for a Footrest, of which the following is a specification, reference being had to the accompanying drawing, forming part hereof.

Fig. 2 is a longitudinal section of the same on line 2—2 of Fig. 1.

I claim:

The ornamental design for a foot rest, substantially as shown.

In testimony whereof I have affixed my signature.

FRANK M. NOONAN.
